US00D631536S

(12) **United States Design Patent**
Wiegel et al.

(10) **Patent No.:** **US D631,536 S**
(45) **Date of Patent:** ** *Jan. 25, 2011

(54) **FAN BLADE**

(75) Inventors: **Aaron J. Wiegel**, Benton, IA (US);
Jason Dondlinger, Bellevue, IA (US);
Ronald P. Snyder, Dubuque, IA (US);
Joseph Korman, Dubuque, IA (US);
John Moore, Marceline, MO (US);
Randy Ward, Chula, MO (US); **Donald P. Grant**, Dubuque, IA (US)

(73) Assignees: **Rite-Hite Holding Corporation**,
Milwaukee, WI (US); **Moore Fans, LLC**, Marceline, MO (US)

(**) Term: **14 Years**

(21) Appl. No.: **29/337,429**

(22) Filed: **May 21, 2009**

(51) LOC (9) Cl. **23-04**
(52) U.S. Cl. **D23/413**

(57) **CLAIM**

The ornamental design for a fan blade, as shown and described.

DESCRIPTION

FIG. 1 is a perspective view of the fan blade showing one example of our new design.

FIG. 2 is a perspective view of the fan blade attached to a multi-blade fan assembly.

FIG. 3 is a top view of the fan blade.

FIG. 4 is a bottom view of the fan blade.

FIG. 5 is a front view of the fan blade.

FIG. 6 is a back view of the fan blade.

FIG. 7 is a right end view of the fan blade; and,

FIG. 8 is a left end view of the fan blade.

The features shown in broken lines are for illustrative purposes only and do not form part of the claimed design.
